UNITED STATES PATENT OFFICE.

WILLIAM S. ROMME, OF NEW YORK, N. Y., ASSIGNOR OF ONE-HALF TO WALTER I. PLUNKETT,
OF NEW YORK, N. Y.

AEROPLANE.

No. 920,085.

Specification of Letters Patent. Patented April 27, 1909.

Application filed December 18, 1908. Serial No. 468,122.

To all whom it may concern:

Be it known that I, WILLIAM S. ROMME, a citizen of the United States, residing at New York, in the county of New York and State of New York, have invented certain new and useful Improvements in Aeroplanes, of which the following is a full, clear, and exact specification.

This invention relates to improvements in aeroplanes or machines adapted for flying through the air and provided with means for floating or moving in or on water and for running or traveling on land, of such form and construction that the aeroplane will automatically maintain its equilibrium under all conditions, thereby reducing to a minimum the possibility of accidents or injury to the apparatus and operator.

One object of the invention is to provide an improved aeroplane having a large inverted bell-shaped, flaring bearing surface against the lifting pressure of the atmosphere, and which at the same time presents as little resistance to an aerial flight as is consistent with a strong and practical construction.

Another object of the invention is to provide the machine with means for propelling it vertically for the purpose of lifting the machine to any desired height in the air.

Another object is to provide means for driving or propelling the aeroplane through the air, and also means for locomotion on the earth's surface, as well as means for preventing the sinking of the apparatus should it descend into water, and means for floating or moving the same in or on water.

Another object is to embody in my improved aeroplane such proportions and distribution of weights and parts as will tend at all times to automatically maintain the equilibrium of the aeroplane, and which will not allow any other than a horizontal position.

Another object of the invention is to provide means for governing the direction of flight of the aeroplane, and to allow the same to ascend and descend without serious shock to the apparatus.

The foregoing objects, as well as other objects of my invention, will be more fully understood from the following description and accompanying drawings, in which—

Figure 1 is a plan view, partly broken, of an aeroplane or air ship or flying machine,

embodying my invention in its preferred form. Fig. 2 is a side elevation thereof, partly broken away, with the canvas or superstructure shown in section; and Fig. 3 is a side view of the aeroplane.

Referring to Fig. 2 of the drawings, the inverted bell-shaped, flaring bearing surface, or hollow cone or funnel, 1, is provided with a series of ring members 2, 3 and 4, connected by means of ribs 5 forming the skeleton frame for supporting the canvas 6. This inverted bell-shaped structure possesses the advantage of presenting a very large and almost horizontal surface 7, against which the lifting power or pressure of the air acts, while the neck 8 of the body of the apparatus, due to being round and relatively small in comparison with the general proportions of the apparatus, presents a minimum resistance to the flight. Preferably, but not necessarily, the skeleton frame is made of bamboo covered with canvas, silk or other suitable material, but such parts of the frame 1 which support the machinery and other mechanism, may be made out of aluminum, or other light but strong material. The particular means for fastening the parts together have not been shown in the drawings, as they are of no importance but will vary greatly according to practice, the size of the aeroplane, and the specific material used.

The lowermost ring member 2 supports a platform 9 upon which is mounted in this instance four motors 10, 10, 11, 11. These motors are shown diagrammatically only, and may be of any suitable kind and construction, preferably of the internal combustion type.

It will be understood that I may employ a single motor with four cylinders, or any other means of motive power. The necessary appurtenances, such as fuel supply, connections and controlling elements, are also omitted for the sake of clearness, as they may be readily purchased in the open market.

For the purpose of lifting the machine into the air and for vertical propulsion, I employ in this instance two propellers 12, 12, each of which is mounted on a shaft 13, 13, suitably supported by stays, rods or otherwise fastened to the ribs 8, and the said shafts 13, 13 are each driven by its respective motor 10, 10, through bevel gears 14 and 15. For horizontal propulsion I employ two propellers 16, 18, carried by horizontal shafts 17, 17, suitably supported,

these shafts being driven from the motors 11, 11, one separately from the other, by means of sprocket gears 18, 19, and chain 20. As each of the above mentioned propellers 5 is driven from its own motor independently of the others, it will be seen that I can at any time run the machine by one or all of the said propellers, thus accommodating the motive force to the particular circumstances 10 of the atmosphere, such as strength of wind and direction thereof, and of variable air currents, and also as to the particular height over the earth's surface in which the flight takes place, &c. It will be understood, of course, that I may use more than two propellers in each of the instances just referred to, and that the means for driving the same 15 may be changed accordingly.

For the convenience of the operator a 20 basket or other suitable receptacle 21 is carried below the aeroplane, and the said basket is provided with a bottom 22 and with ample space for the operator and for necessary appurtenances, tools, provisions, 25 etc., which he may desire to carry with him on his journey. In Fig. 2 I have indicated a lever 23 as a means by which the various motors may be controlled, but it will be understood that one or more levers may be 30 employed for each motor, depending upon the particular arrangement of the mechanism. For controlling and steering the aeroplane, I provide a rudder 24 mounted in a ball and socket joint 25, which is fastened to 35 one of the uprights or ribs 26, which ribs also support the basket or receptacle 21. The said basket is also supported by guide ropes 27, or the like, preferably made of piano wire, or similar strong material. The rudder 40 24 is also provided with a steering wheel 28. By reason of the ball and socket joint construction provided for the rudder, the operator is enabled to steer the aeroplane in any possible direction.

45 Fastened to the basket 21 by means of rods 29 is a circular rail 30, in which are mounted hollow spheres 31 in such a manner that the latter will revolve or rotate around a horizontal central axis at right angles to 50 the axis of the shaft 17, and to this end the said hollow spheres are mounted on bearings 32 in the said rail. The purpose of these hollow spheres, as will be readily seen from Fig. 2, is to provide means for allowing the 55 aeroplane to be propelled on land, and also to obviate any serious shock to the apparatus when the same descends or ascends, and, by reason of the said hollow spheres 31 a gradual slanting rising or descending motion is made 60 possible. Also, should the aeroplane descend on water, or by any accident run from land into water, the said hollow spheres 31 are so constructed and calculated in their dimensions that they will support the 65 weight of the aeroplane on the water and

thereby act as pontoons or floats for preventing the aeroplane from sinking into the water and also preventing the possible drowning of the operator.

The skeleton frame may be attached to 70 the rail 30 by means of strong piano wires 33, and it will be understood that the various ribs, rods, guide ropes, &c. may be arranged in other ways than the one shown in the drawings, as may best suit the size of the 75 aeroplane and the material used in its construction.

An important feature of this invention 80 consists in the very form of the apparatus itself and in its being so calculated and proportioned that the center of gravity centers in the vertical central axis through the inverted bell-shaped frame 1, and that the center of gravity is below the platform 9, so that it will be next to impossible for the aero- 85 plane to upset.

The operation of the aeroplane is very easily understood from the drawings, but in practice the motors 10, 10 are first started in motion, which in turn cause the propellers 90 12, 12, to rotate and the machine is thereby lifted into the air. It will be observed that in this instance the hollow space of the inverted bell-shaped surface allows the air to escape down through the machine, which 95 materially aids the ascent, as the only surface presenting resistance to the air in making the ascent is the upper surface of the member 7. When the proper or desired height has been attained or before, the 100 operator may start the motors 11, 11, which will cause the propellers 16, 16 to move on the shafts 17, 17, and which will then propel the aeroplane in a horizontal direction. Depending upon the circumstances of the flight, 105 the operator may cut out the vertical propellers and run the machine by the horizontal propellers only, and if, through some cause, the rudder 24 should be insufficient to effect the desired change in direction, the 110 operator may assist in the steering of the machine by using the propellers on the one or the other side of the apparatus, as may be deemed expedient.

It will be understood that my invention 115 may be embodied in various other forms and modifications not herein shown or described without departing from the spirit or scope thereof, and I do not wish to be considered as confining myself to the exact construction, 120 instrumentalities or materials herein shown and described.

Having thus described my invention, what I declare as new and desire to secure by Letters Patent, is:

1. The combination of an inverted bell-shaped structure comprising a skeleton frame provided with ribs covered with silk, having an opening at the top and bottom so arranged that the flaring horizontal portions 130

- of said inverted bell-shaped structure form the resistance for the atmospheric pressure, a round body portion provided with a plurality of ring members connected to said body portion by means of ribs, a basket suspended from said frame, a circular rail provided with a plurality of hollow spheres, and means for propelling said inverted bell-shaped structure through space.
- 10 2. In an aeroplane, the combination of a funnel shaped frame covered with canvas, a round body portion provided with a plurality of ring members, a basket suspended from the lowermost ring member, a circular rail supported by said basket, and a plurality of rotatable hollow spheres.
- 15 3. The combination of a cone-shaped structure provided with a circular rail, a plurality of rotatable hollow spheres mounted in bearings on said circular rail, and means for propelling said cone-shaped structure through space.
4. The combination of a cone-shaped structure provided with a circular rail, a plurality of rotatable hollow spheres mounted in bearings on said circular rail, means for propelling said cone-shaped structure through space; and means for steering said cone-shaped structure.
- In testimony whereof I affix my signature, 20
in presence of two witnesses.
- WILLIAM S. ROMME.
